ATTORNEY.

UNITED STATES PATENT OFFICE

107,350

DESIGN FOR A DIRECTIONAL SIGNAL LAMP

Edward T. Condon, New York, N. Y.

Application April 6, 1937, Serial No. 68,577

Term of patent 7 years

To all whom it may concern:

Be it known that I, Edward T. Condon, a citizen of the United States, residing in New York, in the county of New York and State of New York, have invented a new, original, and ornamental Design for a Directional Signal Lamp, of which the following is a specification, reference being had to the accompanying drawing, in which

Fig. 1 is a front elevation of the directional signal lamp, and Fig. 2 is a plan thereof, showing my new design.

I claim:

The ornamental design for a directional signal lamp, as shown.

EDWARD T. CONDON.
